SKEWER FOR ROASTING MEAT

Walter M. Novak, 222 SW. Birdhill Road,
Portland, Oreg. 97219

Filed July 15, 1966, Ser. No. 3,087

Term of patent 14 years

(Cl. D44—29)

FIG. 1 is a side elevational view of a skewer for roasting meat, showing my new design;

FIG. 2 is a top plan view;

FIG. 3 is an enlarged scale front elevational view; and

FIG. 4 is an enlarged scale rear elevational view.

I claim:

The ornamental design for a skewer for roasting meat, as shown.
